(57) **CLAIM**

The ornamental design for a microphone, as shown and
described.

DESCRIPTION

FIG. 1 is a top, front, right perspective view of a microphone
showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The even-length broken lines immediately adjacent to the
shaded area define the bounds of the claimed design and
form no part thereof. The remaining even-length broken
lines show portions of the microphone that form no part of
the claimed design.
